UNITED STATES PATENT OFFICE.

FLORENCE I. HAMMOND, OF CHICAGO, ILLINOIS:

DESIGN FOR A BRACELET.

Application filed April 3, 1925. Serial No. 13,008. Term of patent 7 years.

To all whom it may concern:

Be it known that I, FLORENCE I. HAMMOND, a citizen of the United States, residing at Chicago, in the county of Cook and State of Illinois, have invented a new, original, and ornamental Design for Bracelet, of which the following is a specification, reference being had to the accompanying drawings, forming a part thereof.

Fig. 1 is a top plan view of the bracelet, and

Fig. 2 is a side view of the bracelet.

I claim:

The ornamental design for a bracelet as shown.

In witness whereof, I hereto subscribe my name this 30th day of March, 1925.

FLORENCE I. HAMMOND.
